UNITED STATES PATENT OFFICE

CHARLES RICHTER, OF MOUNT VERNON, NEW YORK, ASSIGNOR TO CHATHAM METAL SPINNING AND STAMPING CORPORATION, A CORPORATION OF NEW YORK

DESIGN FOR A CEILING-LIGHT FIXTURE

Application filed May 18, 1929. Serial No. 31,289. Term of patent 3½ years.

To all whom it may concern:

Be it known that I, CHARLES RICHTER, a citizen of the United States, and a resident of Mount Vernon, N. Y., have invented a certain new, original, and ornamental Design for a Ceiling-Light Fixture, of which the following is a specification, reference being had to the accompanying drawing, forming part thereof.

Fig. 1 of the drawing is a bottom plan,

and Fig. 2 is a side elevation, showing my new design. Only a portion of the completed design is shown in each of the figures, it being understood that the uncompleted portion involves a mere repetition of that part more fully shown.

I claim:

The ornamental design for a ceiling light fixture substantially as shown.

CHARLES RICHTER.
